Search Report issued in ROC (Taiwan) Design Patent Application No. 107302413 dated May 1, 2019.

Primary Examiner — Derrick E Holland

(57) **CLAIM**

The ornamental design for a busbar-less solar cell, as shown and described.

DESCRIPTION

FIG. 1 is a top perspective view of a busbar-less solar cell showing our new design;

FIG. 2 is a bottom plan view thereof;

FIG. 3 is a top plan view thereof;

FIG. 4 is a right side elevation view thereof;

FIG. 5 is a left side elevation view thereof;

FIG. 6 is a back elevation view thereof; and,

FIG. 7 is a front elevation view thereof.

All elements shown in the top plan view of FIGS. 1 and 3 are structural lines on the surface and are flat with the top surface.

1 Claim, 3 Drawing Sheets
